UNITED STATES PATENT OFFICE.

JONATHAN T. BROWN, OF MARBLEHEAD, MASSACHUSETTS, ASSIGNOR, BY MESNE ASSIGNMENTS, TO KRENTLER-ARNOLD HINGE LAST COMPANY, OF DETROIT, MICHIGAN, A CORPORATION OF MICHIGAN.

APPARATUS FOR FORMING SECTIONAL LASTS.

No. 906,378.

Specification of Letters Patent.

Patented Dec. 8, 1908.

Application filed May 27, 1901. Serial No. 62,051.

To all whom it may concern:

Be it known that I, JONATHAN T. BROWN, of Marblehead, in the county of Essex and State of Massachusetts, have invented certain new and useful Improvements in Apparatus for Forming Sectional Lasts, of which the following is a specification.

Prior to my invention, it has been the usual practice in the manufacture of hinged lasts, to first turn from a block of wood the entire last and then cut it transversely into two sections. These sections were then recessed at the top to permit the heel section to move upward and provide abutting members below the pivotal point of the last, the sections being bonded by a hinge. A last is of such irregular form that it has been found in practice, prior to my invention, exceedingly difficult and expensive to properly align and bond the two sections after they have been separated, as above described.

The purpose of my invention is to provide a machine for making such sections independently from a block having first formed thereon the surface that bears a predetermined relation to some surface having a useful function in the last.

In following my invention, I separately turn and produce complemental last sections, each fore-part being turned to aline with, and accurately fit a standard heel-part.

In carrying out my invention, I form each section with a predetermined face, before putting it into the lathe, so that either section can be secured to the chuck herein-after described, with its predetermined face against the face of the chuck. The same chuck is used for turning the fore-parts and the heel-parts, and may be said to represent the face of the heel-part when the fore-part is being turned, and the face of the fore-part when the heel-part is being turned. The predetermined face is formed at one end of the block. The fore-part sections and heel sections, faced as aforesaid, are turned independently from separate blocks or pieces of stock upon a specially organized machine, hereinafter described, by which and by means of the predetermined face of the block and the chuck, each section can be turned with its axis or its axis of rotation, when in the chuck, bearing a predetermined relation to the said predetermined face of

the section. The predetermined face of the heel-section bears a predetermined relation 55 to the said predetermined face of the fore-part section, and the longitudinal axis of one section bears a predetermined relation to the longitudinal axis of the complemental section, so that the axis of the completed 60 last is the same as if the last had been turned solid and never divided. These relations of axes and faces are maintained throughout the making and assembling of the sections or parts of the last. The fore- 65 parts and heel-parts turned as described, when assembled, accurately fit in a predetermined way with their faces and surfaces in proper position and alinement, their abutting ends being a predetermined residue of 70 their respective predetermined faces in relation to which they were turned and assembled.

It is not essential that the predetermined face referred to should subsequently be retained as a whole in the section, as the inner end of the section together with a portion of the face may be afterwards beveled or shaped in accordance with the variety of last being manufactured. This face, or its equivalent, 75 however, during the process of manufacture, is essential and serves as a gage in relation to which the various dimensions, shapes and alinement of lasts are made. In addition to the predetermined face, I form in the said 80 face near the center, two holes which engage pins on the chuck. These holes are preferably bored at right angles to the predetermined face, and not only serve as means by which the block is turned, but in connection 85 with the flat face, serve as means by which the block is accurately adjusted against the chuck and in the templets employed in the operations subsequent to turning, the said 90 templets preferably having, like the chuck, 95 a flat face with two pins projecting at right angles to said face to enter said holes. Instead of the pin and holes I may employ any other suitable means for the described purpose. Further, the principle of employing the flat face may be variously modified. For convenience and certainty of results, I prefer the face above described and the hole and pin construction.

It will be evident from the foregoing, that, 105 when a fore-part is being turned, the chuck

stands in relation of the heel section for that fore-part, and vice versa, so that when a fore-part and heel-part have been turned and finished, necessarily, their supplemental surfaces and faces are accurate in fit and alinement.

In manufacturing sectional lasts, prior to my invention, it has been customary, as heretofore described, to turn the last precisely 10 the same as solid lasts, and thereafter cut up the lasts. In making the solid lasts, or in making sectional lasts, the last is turned with its axis running from the toe to a point substantially near the central part of the 15 heel portion. In cases where there was but little spring, the axis running from the toe to the central part of the heel, above referred to, would pass through the lower part of the rear face of the fore-part, instead of the 20 central part. If the last being turned was the same size as the model, this position of the axis would develop no particular difficulty. It is impracticable, however, to have a model for each size, the practice being to 25 have one model for each style of last, and then by the reproducing method of the last-turning machine, to make lasts of all sizes of the same style as and from that particular model, in order to have a complete set of 30 sizes of a last of that style.

Owing to the irregular contour of lasts, it is desirable, for many reasons, among which may be mentioned making lasts of a larger or smaller size than the model, to 35 turn the last about an axis which extends in a line from the center of the toe backward and upward to substantially the center of the material at the end engaged by the chuck. By this means when sections of a 40 larger or smaller size than the model are turned, there is no excessive exaggeration or diminution of the dimensions of the model, as would be the case if the axis at the chuck were near one surface of the block, or materially off-center. This result I obtain by 45 turning the fore-part and the heel-part separately, by means of the described chuck and pin construction and the face and central holes in the block, thereby having the material of the last evenly distributed about its 50 axis of rotation while in the lathe, the chuck practically constituting the supplemental heel-part, and vice-versa. The axis of the last is also correctly maintained, and the 55 axis and surfaces of one part correctly aline with and form a continuation of those of the other part or section. In a word, by my invention I produce a hinged last in which the measurements, surfaces and alinement 60 are correctly maintained irrespective of the grade or size above or below the model.

Referring to the drawings,—Figure 1 represents a portion of a turning lathe, the pattern wheel and the cutter being shown in full

lines. Fig. 2 represents the chuck, the chuck-carrier, and the last section held in place by the chuck-carrier. Fig. 3 represents a plan view of the chuck-carrier. Figs. 4 and 5 represent the adjustable coupling for the 70 shaft which drives the chuck-carriers by means of which the patterns and the stock may be rotated in exactly the same relation to the pattern-wheel and the cutter. Fig. 6 represents a longitudinal section through the 75 chuck. Fig. 7 represents a longitudinal section through the same, on the line 7—7 of Fig. 6. Fig. 8 represents a section on the line 8—8 of Fig. 6. Figs. 9, 10, 11, 12 and 13 represent the chuck in detail. Fig. 14 80 represents the partially finished fore-part, Fig. 15 represents the end of the finished fore-part. Fig. 16 represents the gage plate which is clamped against the end of the section. Fig. 17 represents in full lines a fore- 85 part block. Fig. 18 represents the fore-part as finished by the lathe. Fig. 19 represents a heel-block. Fig. 20 represents a heel-part as finished by the lathe. Fig. 21 represents a heel-part and a fore-part as finished by the 90 lathe, showing the relation of the supplemental faces with the hole and pin construction, the pins appearing at c'.

Referring to the drawings, which illustrate one embodiment of the invention, 95 Fig. 20 represents the usual swinging frame which carries the pattern and the stock to be turned, said frame being oscillatory with relation to the pattern-wheel 21 and the cutter 22, which are mounted and rotated in the usual manner. The frame is provided with the end bars 23, 24, and the intermediate cross-bars, 25, 26, 27. In the bars 23 and 26 is journaled a split shaft 28—29, the sections of which are connected by a coupling which I shall subsequently describe. Said shaft is provided with the usual pulley 30 driven by a belt 31, and on the shaft are pinions 32, 33 intermeshing respectively with gears 34, 35 on the chuck-carrying shafts 36, 37. The shaft 36 is journaled in bearings in the end bars 23 and the cross-bars 25, the shaft 37 being journaled in the cross-bars 26, 27. On the frame are two adjustable cross-bars 38, and 105 39, the latter being adjusted by a screw-bar 40 and being held in place after adjustment by a set screw 41. These cross-bars 38 and 39 carry the studs or spindles 42, 43 which hold the pattern and the stock against their respective chucks and permit their rotation, 110 said spindles having their axes coinciding with the axes of the shafts 36 and 37.

As thus far described, the machine does not differ in any essential point from the well-known turning-lathe now in general use, except in the mechanism by means of which the shafts 36, 37 may be rotatively adjusted with relation to each other, as will be subsequently explained. On each of the shafts 36, 37 is a universally adjustable chuck, and as the two 115 120 125 130

chucks are similar I shall describe only one of them, reference being now had to Figs. 2 to 13, inclusive.

The end of the chuck-carrying shaft is formed with a round head, which is transversely grooved in the face thereof to provide two flanges 43, 43, the inner faces of which are parallel, as shown in Fig. 9, and the two flanges are likewise grooved inward from the edges to provide curved lips 44, 45. The lips 45 are apertured at 46, 46. Between the flanges 43 is pivoted a lug 47 by means of a screw-pin 48. This lug 47 projects rearwardly from a coupling, consisting of a plate 481 having forwardly projecting flanges 49, 49 whose inner faces are at a right angle to the inner faces of the flanges 43. The lug 47 is beveled from its center toward its edges, as shown in Fig. 7, to permit it to be swung about the screw-pin 48.

50 indicates the chuck proper, which is pivoted between the flanges 49, 49 by a screw-pin 51, so that said chuck has a universal adjustment with relation to the axis 25 of the shaft. Adjusting-screws 52, 52 are passed through the coupling 481 to bear against the rear edges of the chuck 50, to adjust the latter, said screws being secured after adjustment by nuts 53, and the coupling 30 481, together with the chuck adjusted in a direction at right angles to the chuck adjustment, and secured after adjustment by the screws 54, 54, and nuts 55, 55, said screws being passed through the coupling 35 481 and the lug 47, and bearing against the inner wall of the groove formed transversely in the head at the end of the shaft. The front face 56 of the chuck is preferably flat and two pins 57, 57 project forwardly therefrom, as shown, (see Fig. 11). Against the face 56 a gage plate 58 is placed, said plate having apertures 59 to receive the pins 57. Inasmuch as each of the chucks may be universally adjusted, with relation to its shaft, 45 it will be seen that the stock and the pattern may be gripped by the spindle against the chuck, in exactly the same position with regard to each other and the axis of rotation. In order to rotatively adjust the pattern 50 and the stock relatively to each other, the coupling shown in Figs. 2 to 5 is employed for connecting the two sections 28, 29 of the shaft previously referred to. Said coupling consists of two confronting collars 60 and 55 61 rigidly secured to the meeting edges or ends of the shaft 28—29.

Screws 62, 62 are passed through curved slots 63 from the collar 61 into the collar 60. Thus it will be seen that one of said shafts 60 may be rotatively adjusted and timed with relation to the other, after which the two may be rigidly secured by driving the screw 62 home, so as to bind the collars firmly together to prevent them from slipping. 65 This adjustment enables the stock to be ro-

tated in true relation to the rotation of the pattern, and when once made does not require further attention, since this factor is a constant, irrespective of the varying sizes or styles or shapes of the model. This accurate adjustment has not been necessary in lathes employed for making hinged lasts, prior to my invention, since all sizes or styles of lasts were turned to the same fixed axis, and blocks for all kinds of lasts were 70 chucked alike. By my invention, on the contrary, the blocks are differently chucked with relation to the face of the chuck to the axis of rotation and the axis of the last is determined before the block is chucked. The 75 sections being turned with relation to a predetermined face or gage, it is necessary that the block and pattern should rotate in true unison. While such unison of rotation is theoretically possible in a machine, as a practical proposition, some adjusting means are necessary to secure this mode of operation, owing to imperfection of parts, etc. In accordance with my invention, therefore, the pattern dog and block dog are both adjusted 80 alike, not only with respect to the pitch of the face of each dog to the line running from the point of the spindle to the center of the dog face, but also by means of the adjustment between the driving mechanisms of 85 the dogs and each and every point, and the last or block held by the block dog is necessarily in true adjustment to the corresponding point upon the model. These adjustments together with the particular way in 90 which the stock is held to distribute the material of the finished section substantially equal about the axis, enables me to accurately reproduce the sections of different 95 sizes of the model.

100 The process by means of which the last sections are constructed and which includes the operation of the machine above described, is as follows:—The end of the larger portion of the last-block *a* is faced as at *b*, and in the said end are bored, by means of a suitable tool, two parallel apertures *c c*, in substantially the central part of the face, said face *b* and the apertures *c* corresponding to a similar face and similar apertures on the pattern *d*. The pattern *d* is then placed 110 upon the pattern chuck, and the chuck is adjusted until the end of the last is engaged at the proper point by the spindle 42, a slight indentation or hole being made in 115 the said end for this purpose. The pattern is then placed upon the stock chuck with the face of the pattern flat against the plate 58 on the chuck 50. The stock chuck is adjusted until the pattern is in position 120 to receive the point of the spindle in the aforesaid indentation, after which the adjusting devices are locked to hold the chuck continuously in that position so long as that 125 particular style of fore-part or heel-part is 130

being manufactured or turned. The pattern is then replaced in the pattern chuck and the spindle is engaged in the indentation described. The last block or stock is placed upon its proper chuck with the pins 57, 57 entering the apertures *e*, *c* and the face *b* is forced firmly against the face of the plate 58, it being remembered that there is also a plate 58 on the pattern chuck. Then the cross-bars 39 are adjusted to bring the spindle 43 into engagement with the end of the stock. The machine is set in operation, and the stock is turned to form a fore-part or heel-part exactly similar to the pattern, and it will be noted that each time this is done, the axis of rotation of the stock bears a predetermined relation to the flat face at the end of the stock. I do not mean by this that the axis on which each fore-part is turned always bears, in different styles of fore-parts, the same relation to the flat face, for it will be readily seen that right lasts and left lasts are turned on axes which are at different angles to the flat faces, and that differently shaped fore-parts are turned on axes which vary in their relation to the flat face. But it will be noted, however, that if fifty, or any other number of fore-parts of a certain style or shape for a right shoe or a left shoe of a certain size be turned, they will all be rotated on axes bearing the same predetermined relation to the flat face, said face serving as a gage for the operation.

I have illustrated a fore-part in the machine, but it will be understood that the heel-part is constructed in exactly the same way, said heel section being provided with a flat face which is apertured to receive the pins carried by the chuck, as shown in Figs. 19 and 20. It is further to be noted that the stock chuck represents a complementary heel section while a fore-part section is being turned. After the sections have been turned, the squared ends thereof may be beveled or otherwise shaped, this and all subsequent operations being accomplished by placing the said flat faces and their holes in engagement with templets that are duplicates so far as their faces and holding members are concerned, of the face and pieces of the stock chuck, thereby maintaining to the end the relationship of the various faces and alinement of the sections and insuring the accurate and proper fitting and alinement of the two sections when assembled.

In Figs. 18 and 20, I have shown the fore-part and heel section as being beveled on the line *e*. In making hinged lasts, the

lower portion of the face *b* is left on both the heel-section and the toe section, since 60 said faces confront each other below the axis of the pintle and meet when they are in normal or operative position. After the sections have been turned, the subsequent steps will depend upon the particular style 65 of last, style of hinge, etc. A description of the subsequent steps is unnecessary beyond the instructions that when the sections are being worked upon to secure surfaces, alinement, fittings, etc., they are held by 70 the described templet, thus in effect having the fore-part held by its complementary heel-part, and vice versa. The holes in the sections may be utilized to position and anchor the hinge. 75

Having thus explained the nature of my invention, and described a way of constructing and using the same, though without attempting to set forth all of the forms in which it may be made, or all the modes of 80 its use, what I claim, and desire to secure by Letters Patent is:—

1. In a last-turning machine, a universally adjustable model-turning chuck, a universally adjustable block-turning chuck, and adjustable means for causing the two chucks to travel in unison. 85

2. In a last-turning lathe, a chuck comprising a chuck spider, a web pivoted thereon, means for adjusting said web about its 90 pivot, a dog pivoted to said web, means for adjusting said dog about its pivot, the said pivots being arranged at an angle to each other, whereby the dog may be adjusted to position the axis of the model or block at 95 any desired position with respect to the axis of rotation of the chuck.

3. In combination with the co-operative elements of a machine for turning irregular forms, a model last fore-part, formed with 100 an abutting face having a definite relation to the contour and axis of the last and adapted to engage a complementary face upon a heel-part, means for holding said abutting face or part arranged to position the toe 105 center or toe plate of the model at a point to be engaged by the toe spindle, and complementary means for supporting a forepart last-block, having a corresponding abutting face or part. 110

In testimony whereof I have affixed my signature, in presence of two witnesses.

JONATHAN T. BROWN.
